(54) **HORSE POWER**

(76) Inventor: **Rufus Porter**

Rufus Porter of Billings, Massachusetts
Letters Patent.

The Schedule referred to in these Letters Patent and making part of the same, containing a description in the words of the said Rufus Porter himself of his improvement "in the flexible Horse power".

To all to whom these presents shall come, I say I know that at Rufus Porter of Billings in the County of Middlesex and State of Massachusetts have invented a new and useful portable Horse Power or machine for the purpose of applying the Power of a Horse to other machinery, and that the following is a full and exact description of the construction and operation of said machine as invented by me.

At first floor (or end floor) is composed of seventeen pieces of plank, each plank being eighteen inches long twelve inches wide and one inch thick, which planks are connected together by the following method: On one side of each plank are two cleats secured to the plank by nail, or screws, each cleat being one foot in length, three inches wide and one inch thick, the outward edge of each cleat being within one fourth of an inch of the end of the plank and to this outward edge is a strap of iron attached by screws, each strap being thirteen inches long one and one fourth inches wide and one fourth of an inch thick, the strap being wider than the thickness of the cleat, a rabbit is cut in the end of the plank to accommodate one edge of the strap, that the other edge may be even with the face of the cleat, through each end of each strap is a round hole half an inch in diameter, the centre of the hole being parallel with the edges of the the plank, the edges of each two planks being placed in contact, (the ends of the straps passing a little by each other that the holes of each two may come together) a half inch iron rod having one inches long is passed through the ends of each four straps, thus connecting together the planks by hinge joints.

On each end of each rod outside of the straps, is a cast iron wheel four inches in diameter and one inch thick which is secured on the rod by a pin passing through the end of the rod outside of the wheel. All the planks having been placed side by side and connected as above described, the two outside planks are then brought together and hitherto connected thus forming a bell or end floor. This floor is supported by frames as follows:

Two sills each eight feet and six inches long, three inches wide and two inches thick, are placed on the ground parallel to each other and being eighteen inches apart are connected by two narrow cross timbers which are turned to each side. Directly over and twenty two inches above the sills are two plates of the same dimensions as the sills. Each plate is supported by three posts which are turned back to the sills and to the plates, two of them being set thirteen inches from the ends of the sills and the other in the center, these posts being four inches wide and one and a half inches thick, are set into the timbers and of the sills, leaving a space twenty one inches between each post and its plate position. To the inside of each three posts a nail is attached by iron, or bolts, the nail is driven in so deep by one and a half inches, thick and each end after passing the post is turned, curving downward, forming a semi-circle of thirteen inches diameter. These will support a part of the friction wheels of the belt floor while another part rests on the sills below. These sills are fixed five inches below the plates and the length of them must be sufficient to fill the space between the friction wheels on each side of the floor. The frame is further supported by a plank eight inches wide which passes from one center post to its opposite being turned by double tenons to each immediately below the sills which are also thus by supported. An iron shaft thirty inches in length passes horizontally through the opposite posts at one of the frames at a point central to the motion of the parts of the floor as they pass over the convex ends of the sills. This shaft is one inch and a half square, being rounded however where it passes through the posts, and extending three inches beyond the posts on each side for the purpose of carrying and carrying a gear or hand wheel. On this shaft inside of the posts are two straps consisting of four arms each, the ends of which arms being one foot distant from each other having corresponding notches on them taken to the rods of the belt floor inside of the straps thus securing motion from the floor, which is communicated by the gear and wheel to other machinery. When the planks composing the floor are put in motion by the feet of the men each friction wheel is caused to turn after rolling the length of the said planks and will back on the sills to the forward end, whence it will

comes to place on the rails. The operator of such cart is provided with a thin plate of iron, and the wheels are guided on the rails by a small square wood of iron being nailed on each rail also bending over the outer or outside of the track of the wheels. Back track of the bell floor is sheathed by a piece of pine board three fourths of an inch thick and of a length and breadth corresponding with those of the planks being nailed on the upper or outward side of the planks, the latter each being two inches square and one foot high and supported rearwardly (thereon each side of the frame) by staples or strips of iron, which are attached to the outward sides of the belly and of the plates. Two of these staples being at or near the fore corners of the frame each there of them support a small rail for the purpose of keeping the cart in place, when he walks on the floor, the side rail consisting of pine board six inches wide being secured to the inside of the staples and near the top, by screws. Two other boards or planks are also attached to the inside of the staples immediately above the floor, the lower edges of the planks coming inside of the wheels for the purpose of securing the wheels from damage by the feet of the men. Two uprights each being two feet long and two inches square extend rearward and are secured by bolts one to the top forward and the other to the two back staples about three feet above the level of the floor, one of them being for the draught of the horses and the other for holding back. Note. That well of the machine in which the shaft is situated is called the front end. Some each end of each upright has a small brace extending to the front of each of the two back staples, and the plate, the end of the brace, resting on the plate and bearing against the staples sufficiently support the upper work in sustaining the draught of the horses. The staples and other upper work may be readily taken down occasionally for the greater convenience in moving the machine from place to place.

The inventors, which it claims as original to us, the application of the fore-mentioned bell floor, the kind of planks, the method of securing the same, staples of staples and the application of staples consisting of staples, as herein described.
